UNITED STATES PATENT OFFICE.

JAMES J. WOOD, OF FORT WAYNE, INDIANA, ASSIGNOR TO GENERAL ELECTRIC COMPANY, A CORPORATION OF NEW YORK.

DESIGN FOR A COMBINATION WASHING-MACHINE TUB AND FRAME.

• 60,843.

Specification for Design.

Patented Apr. 11, 1922.

Application filed May 6, 1920. Serial No. 379,420. Term of patent 14 years.

To all whom it may concern:

Be it known that I, JAMES J. Wood, a citizen of the United States, residing at Fort Wayne, in the county of Allen, State of Indiana, have invented a new, original, and ornamental Design for Combination Washing-Machine Tubs and Frames, of which the following is a specification.

In the accompanying drawing, Fig. 1 is a front, perspective view of a combination

washing machine tub and frame showing my new and original design and Fig. 2 is a rear, perspective view of the same.

What I claim is—

The ornamental design for a combination washing machine tub and frame.

In witness whereof, I have hereunto set my hand this 1st day of May, 1920.

JAMES J. WOOD.
